(57) **CLAIM**

The ornamental design for a shelf, as shown and described.

DESCRIPTION

FIG. 1 is a top perspective view of a shelf in accordance with the present invention;

FIG. 2 is a close-up view of a portion of the shelf identified in FIG. 1;

FIG. 3 is a bottom perspective view of the shelf in accordance with the present invention;

FIG. 4 is a close-up view of a portion of the shelf identified in FIG. 3;

FIG. 5 is a front elevation view of the shelf in accordance with present invention;

FIG. 6 is a close-up view of a portion of the shelf identified in FIG. 5;

FIG. 7 is a rear elevation view of the shelf in accordance with present invention;

FIG. 8 is a top plan view of the shelf in accordance with present invention;

FIG. 9 is a close-up view of a portion of the shelf identified in FIG. 8;

FIG. 10 is a bottom plan view of the shelf in accordance with present invention;

FIG. 11 is a close-up view of a portion of the shelf identified in FIG. 10;

FIG. 12 is a left side elevation view of the shelf in accordance with present invention;

FIG. 13 is a close-up view of a portion of the shelf identified in FIG. 12;

FIG. 14 is a right side elevation view of the shelf in accordance with present invention; and,

FIG. 15 is a close-up view of a portion of the shelf identified in FIG. 14.

(Continued)

The broken lines in the drawings depict portions of the shelf that form no part of the claimed design; the dash-dot-dash broken lines in the figures demarcate a boundary and form no part of the claimed design.
